UNITED STATES PATENT OFFICE.

JOHN TUOHIMAA, OF IRONWOOD, MICHIGAN.

GARMENT-HANGER.

1,233,001.

Specification of Letters Patent. Patented July 10, 1917.

Application filed January 10, 1917. Serial No. 141,593.

To all whom it may concern:

Be it known that I, JOHN TUOHIMAA, a citizen of Russia, Finland, residing at Ironwood, in the county of Gogebic, in the State 5 of Michigan, have invented certain new and useful Improvements in Garment-Hangers, of which the following is a specification.

This invention relates to improvements in garment hangers. One object of the invention is to provide a device of this class that is simple in construction, cheap to manufacture and efficient in operation. With the foregoing and other objects in view the invention consists in the combination and arrangement of parts to be hereinafter fully described in this specification, pointed out in the appended claims and illustrated in the accompanying drawing which forms a part of the specification and in which—

20 Figure 1 is a front elevation of the invention illustrating its application.

Fig. 2 is a top plan view.

Figs. 3 and 4 are end views showing some of the parts in altered positions.

25 Like reference characters denote corresponding parts throughout the several views.

My garment hanger comprises the supporting strip or frame 1 which preferably is beveled as at 2 along one of its longer 30 edges. To the said frame 1 the hook bar 3 is movably secured by the staples or fasteners 4. The ends of the hook bar are bent outwardly or away from the frame 1 and then bent again at 4^a and terminate in stop 35 hooks 5 which, in one position, may engage with the beveled portion 2 of the frame 1 to limit the rotary movement of said hook bar. The hook bar is formed with a plurality of integral garment-receiving hooks 6 40 and with an integral handle 7 by means of which it may be rotated in its bearings. The said hook bar, further, is formed with a plurality of offsets 8 to which other garment hooks 9 are made fast. Each hook 9 comprises a heel portion 10 adapted, in the normal position of the hook bar shown in Fig. 3, for engagement with the frame 1, the said hook beyond said heel being curved about the hook bar 3 and secured fast thereto at 45 11 and then being curved away from the hook bar as at 12 and then formed with a regular substantially semi-circular curve 13 and, beyond same, terminating in the toe 14 adapted to carry a garment.

50 With the device in the position illustrated

in Figs. 1, 2 and 3 a garment, such as a hat, coat (see dotted lines in Fig. 1) or like garment may be hung upon the hooks 6 or 14; and if desired an umbrella, cane or package may be retained between the curved portion 60 13 of the hook 9 and the frame 1. To place or remove the umbrella or package the rod 3 and connections are moved by handle 7 into the position shown in Fig. 4 and the article then raised into such position that 65 it will be carried by the curved portion 13 of the hook 9 and have a bearing against the frame 1 when the device again assumes its normal position. Any garments carried by the hook 6 and 14 will cause a downward pull upon those hooks which will tend to hold the device more firmly in normal position and to thereby increase the holding or retaining capacity of the curved portions 70 13 of the hooks 9.

75

What is claimed is:—

1. In a garment hanger, a frame, a hook bar movably carried by said frame, an operating handle integral with said hook bar, garment-receiving hooks formed integral 80 with said hook bar, and individual hooks fast to said hook bar and formed with heels for frictional engagement with said frame.

2. In a garment hanger, a frame, a hook bar movably carried by said frame, an operating handle for said hook bar, garment-receiving hooks formed integral with said hook bar, and hooks fast to said hook bar, said last named hooks being formed with heels and with intermediate regularly curved 90 portions.

3. In a garment hanger, a frame, a rotary hook bar carried by said frame, terminal hooks formed on said hook bar for engagement with said frame, an operating handle 95 for said hook bar, garment-receiving hooks formed integral with said hook bar, and hooks fast to said hook bar, said last named hooks being formed with heels and with regularly curved portions for coöperation 100 with said frame to retain an article.

In testimony that I claim the foregoing as my own I have hereto affixed my signature in the presence of two subscribing witnesses.

JOHN TUOHIMAA.
